UNITED STATES PATENT OFFICE

105,860

DESIGN FOR A SLED

Clarence E. Garton, Sheboygan, Wis.

Application May 8, 1936, Serial No. 62,544

Term of patent 3½ years

To all whom it may concern:

Be it known that I, Clarence E. Garton, a citizen of the United States, residing in the city of Sheboygan, in the county of Sheboygan and State of Wisconsin, have invented a new, original, and ornamental Design for a Sled, of which the following is a specification, reference being had to the accompanying drawing, forming part thereof.

Figure 1 is a plan view of a sled and Figure 2 is a perspective view thereof, showing my new design.

I claim:

The ornamental design for a sled, as shown.
CLARENCE E. GARTON.
